UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

NIGHT-LATCH.

SPECIFICATION forming part of Letters Patent No. 625,073, dated May 16, 1899.

Application filed January 13, 1899. Serial No. 702,064. (No model.)

To all whom it may concern:

Be it known that I, HENRY G. VOIGHT, a citizen of the United States, residing in New Britain, in the county of Hartford and State 5 of Connecticut, have invented certain new and useful Improvements in Night-Latches, of which the following is a specification.

My invention relates to improvements in night-latches; and the main object of my improvement is simplicity and economy in construction, whereby I make the spring for the latch-bolt also serve as the spring for the frictional bearings of the sliding stop.

In the accompanying drawings, Figure 1 is a rear elevation of my latch with the cap-plate removed. Fig. 2 is a sectional plan view of the same with the cap on, the plane of section being indicated by the line *x x* in Fig. 1. Fig. 3 is a rear elevation showing a portion 15 of the case, the spring, and the stop. Fig. 4 is a like view of a portion of the case and the knob for the stop, the stop itself being removed. Fig. 5 is a vertical section on the line *y y* of Fig. 3. Fig. 6 is a view corresponding to Fig. 3, but showing a modified form of stop; and Fig. 7 is a like view showing another modified form of stop.

A designates the body of the case, and B the cap, both of which may be of any ordinary form. The knob C and hub D may also be of ordinary form, and so, also, may be the main portion of the latch-bolt 8.

I have illustrated my improvement as applied to a latch; but it is evident that it is 35 equally applicable to a combined latch and lock.

In the present form the latch-bolt 8 is provided with two projections 9 for attaching the spring 10, whereby the said latch-bolt is reversible. The said latch-bolt is also provided with a shoulder 11 on each edge for being engaged by the holding-lug 12 of the sliding stop 10. The said stop also has a slightly swinging movement and is provided with an 45 operating-knob 13, the shank 18 of which extends through a slot in the broad side of the case into said stop, one side edge of said slot having a frictional bearing-face 14, with inclines, as best shown in Fig. 4, for acting in 50 connection with the shank of the knob 13. The latch-case is also provided with a fixed

pin or stud 15, which is received into the longitudinal slot 16 of the stop. Said stop is also provided with an arm 17 for connecting it with the spring 10 by one end, the other end of said spring being connected to the projection 9 on that edge of the latch-bolt, so that the one spring pulls both on the latch-bolt to project it from the case and on the stop to 55 yieldingly hold the frictional bearing-faces of the stop in engagement. It should be noted that the arm 17 of the stop to which the said spring 10 is connected is somewhat above the pin 15, which serves as the fulcrum for the swinging movement of the stop, so that the 60 lower end of said stop swings forward—that is, to the left, as shown—and yieldingly holds the shank 18 of the slide-knob 13 in engagement with the frictional bearing-face 14 on the side of the slot in the latch-case, whereby 65 the sliding stop is held in position at either end of its sliding movement. As shown in Figs. 1 and 2, the latch-bolt is held within the case by the stop, which has its holding-lug 12 in front of one of the shoulders 11 on the 70 latch-bolt. By moving the sliding stop upwardly the knob-shank 18 of the stop-knob 13 yields a little to the right to permit said shank 75 to ride over the incline of the frictional bearing-face 14, and when the stop reaches the upper end of its movement the holding-lug is 80 withdrawn from the latch-bolt and the yielding frictional bearing-face—that is, the knob-shank 18—comes on the upper side of the incline on the non-yielding frictional bearing- 85 face 14 on the case and holds the sliding stop in its disengaged position under the influence of the one spring 10, which serves both for the latch and the stop.

In Fig. 6 I have shown another form of 90 sliding stop for use in connection with a like latch-bolt and spring and which involves in like manner a combined swinging and sliding stop and yielding and non-yielding frictional bearing-faces for said stop, in connection with 95 said spring and latch. 01 designates the sliding stop, having the holding-lug 12 and arm 17 for one end of the spring, the same as in the construction first described; but in this case the shank 18^a of the knob 13, which is 100 rigidly secured to said stop, works in a plane slot in the case, as indicated by broken lines,

and the fulcrum for the slightly-swinging movement of the stop is on said shank instead of the pin 15. The yielding frictional bearing-face 14^a is formed in the body of the stop 5 instead of the case and is provided with inclines like those in the non-yielding face 14 of Fig. 4. Said yielding face acts in connection with a non-yielding face that is formed by one side of the pin 15^a, fixed in the case. 10 The operation is obvious when considered in connection with the operation of the stop first described.

In Fig. 7 I have shown another form of stop embodying the same generic features, in which 15 02 is the sliding stop. It has no swinging movement, but has the same holding-lug 12 for engaging the latch-bolt. The knob-shank 18^b is secured to the stop and, as in Fig. 6, it passes through a plane slot in the case, as 20 indicated by broken lines. Near its lower end said stop is provided with a non-yielding frictional bearing-face 20, with double inclines. I form the yielding bearing-face 14^b with double inclines on a separate or additional 25 piece 21, pivoted to the case at 22 and having an arm 17 for attaching one end of the spring 10. The operation is substantially the same as before. The stop is shown in its downward position for engaging the latch, and it will be 30 seen that the frictional bearing-faces under the tension of the spring 10 hold the stop in this position. On moving the sliding stop upwardly the piece 21 swings on its pivot 22 to permit the frictional bearing-face 20 to pass 35 the opposing face 14^b to withdraw the holding-lug 12 from the latch-bolt, and then said piece swings back again to keep the frictional bearing-faces in engagement, all under the influence of the spring 10, which also acts on the 40 latch-bolt. It will thus be seen that in the construction shown in Fig. 7 the only function of the piece 21 is to furnish the yielding bearing-face 14^b, so that said face may be properly considered as a separate element of the 45 combination. It will also be seen that the non-yielding faces have been transferred from the case to the sliding stop, and yet the combination illustrated in Fig. 7 operates the same as that of the preceding figures and em-

ploys the same means, whereby it is deemed proper to refer to the frictional bearing-faces as separate elements of the general combination, notwithstanding the fact that in Figs. 1 to 6 they are formed integral with other elements instead of in a separate piece. 50

55

It is apparent that some changes from the specific construction herein disclosed may be made, and therefore I do not wish to be understood as limiting myself to the precise form of construction shown and described, 60 but desire the liberty to make such changes as may fairly come within the spirit and scope of the same.

I claim as my invention—

1. In a night-latch, the combination of a 65 case and a latch-bolt with a sliding stop for engaging a shoulder on said latch-bolt, yielding and non-yielding frictional bearing-faces for holding said stop in position, and a single spring serving the double purpose of a spring 70 for the latch-bolt and for the said yielding frictional bearing-faces of said stop, substantially as described.

2. The combination of a case and a latch-bolt with the combined sliding and swinging 75 stop, yielding and non-yielding frictional bearing-faces for holding said stop in position, the said faces being formed the one on the case and the other on said stop, and a single spring for the latch-bolt and said yielding frictional 80 bearing-faces, substantially as described.

3. The combination of a latch-bolt and case, one plate of which is provided with a slot having the non-yielding frictional bearing-face 14, with the stop 0 having a knob-shank secured 85 thereto and passing through said slot in the case for acting on said face 14, a slot 16, a holding-lug 12 and arm 17 for connecting one end of a spring, a pin 15 on the case and within the said slot 16, said pin being located 90 between the said arm 17 and the said knob-shank 18, and a spring, substantially as described.

HENRY G. VOIGHT.
